UNITED STATES PATENT OFFICE.

JOHN S. SPIREWKA, JR., OF MILWAUKEE, WISCONSIN, ASSIGNOR OF ONE-THIRD TO DANIEL C. O'CONNELL AND ONE-THIRD TO JAMES E. O'CONNELL, BOTH OF MILWAUKEE, WISCONSIN.

BURGLAR-ALARM.

1,379,058.

Specification of Letters Patent. Patented May 24, 1921.

Application filed February 28, 1921. Serial No. 448,441.

To all whom it may concern:

- Be it known that I, JOHN S. SPIREWKA, Jr., a citizen of the United States, and resident of Milwaukee, in the county of Milwaukee and State of Wisconsin, have invented certain new and useful Improvements in Burglar-Alarms; and I do hereby declare that the following is a full, clear, and exact description thereof.
- 10 My invention refers to burglar alarms, and it has for its object to provide a simple, economical and effective audible signal alarm attachment for standard door knobs or windows.
- 15 The specific object of my invention is to provide an alarm that can be readily mounted upon a door and associated with the knob shank thereof, whereby an actuating cam can be detachably mounted upon the
- 20 knob shank to thus set off the alarm when the knob is rotated.
- Another object of my invention is to provide a reciprocative spring controlled plunger having a resetting arm extending from
- 25 one end, with means associated with the arm and plunger whereby a percussion cap can be fired by the plunger coincident with the sounding of a bell under control of the resetting arm.
- 30 Another object of my invention is to provide a reciprocative lock and release finger in connection with the plunger, which finger is under control of a cam, detachably secured to the knob shank of a door.
- 35 With the above and other minor objects in view, the invention consists in certain peculiarities of construction and combination of parts, as are hereinafter set forth with reference to the accompanying drawings
- 40 and subsequently claimed.

In the drawings:

- Figure 1 represents a front elevation of a fragment of a door and its knob equipped with an alinement mechanism embodying the
- 45 features of my invention, with parts broken away and other parts in section to more clearly illustrate details of construction, and
- 50 Fig. 2 is a longitudinal sectional view through the same, the section being indicated by line 2—2 of Fig. 1.
- Referring by characters to the drawings, 1 represents a standard door knob provided with a shank 1' mounted upon which shank is a stirrup cam 2, the same being in the

form of a spanner arranged for adjustment 55 upon the knob shank. One arm 2' of the spanner has fitted therein a set screw 3, which serves to bind the cam to the shank. The upper face of the cam is flattened as indicated at 2'', and this flattened face is 60 formed with a central recess into which is fitted a nipple 4 that extends from the lower flattened face of a shoe 5, which shoe constitutes a part of a reciprocative lock and release finger 6.

As best shown in Fig. 2, the upper end of the finger is formed with a looped head 6', the loop in which head is provided with a key receiving recess 6''. The loop is arranged to encircle a firing plunger 7, which 70 plunger is both reciprocatively and oscillately mounted in apertured ears 8 8' that constitute part of a bracket 9. The rear end of the plunger is formed with an angularly disposed resetting arm 7', and the forward 75 end face is adapted to enter a percussion cap socket 10 of a lug 10', which extends from the bracket base.

The bracket 9 is secured by suitable means to the door just above the knob, as shown, 80 and said bracket has secured thereto, in this particular case, a spring controlled bell 11, said bell being of standard type and its spring controlled hammer is released by a button 11'. The actuating parts of this bell are 85 not shown, as they form no part of my invention. The button 11', however, is arranged to be engaged by the resetting arm 7' when the alarm is released for an audible signal. The plunger is under spring control and 90 has fitted thereon a coil spring 12, one end of which coil spring abuts the rear bracket ear 8', and the forward end impinges against a collar 13 that is suitably secured to the plunger. Directly forward of the collar, the 95 plunger has extended therefrom a key 14, which key, when the plunger is retracted and locked under spring pressure, impinges against one face of the finger head 6' whereby the finger is frictionally held in place by 100 the spring pressure against the front ear bracket 8. Hence, it will be noted that when the parts are in their set or locked position, as shown in Fig. 1 of the drawings, should the door knob be rotated in either direction, 105 the flat cam face 2'' will rockingly engage the lower face of the shoe 5, which constitutes a part of the finger, and said finger will

thereby be pushed upwardly. This action causes the loop in the head 6" to shift its position, whereby the key 14 of the plunger 7 is free to shoot forward under spring pressure, and this movement will simultaneously explode a percussion cap that may be inserted in the lug 10', and release the alarm bell 11, due to the fact that the resetting arm 7' of the plunger will engage the button 11' 10 of the bell.

In order to reset the mechanism, after the alarm has been sounded, the operator swings the resetting handle through approximately 45 degrees, whereby the key 14 15 of the plunger 7 will be alined with the recess 6" of the looped aperture in the head 6". The plunger can then be drawn back to its resetting position and when it is again revolved about its axis through approximately 45 degrees, the key 14 will be blocked 20 against forward movement under spring pressure and the resetting arm will position in alinement with the bell button. Thus, the parts are set and ready to be 25 tripped, should the knob be revolved in either directon thereafter.

It will also be noted that the nipple 4 which extends into the socket of the cam serves as a guide or retaining means for the 30 lock and release finger, whereby the same is held in normal alinement. Obviously, I may in some instances connect the actuating cam of the alarm with a window, by means of a runner trained over suitable pulleys, whereby when the window is shifted from its normal position the alarm will be released.

While I have shown and described one exemplification of my invention, minutely 40 as to detail, it is understood that I may vary such detail within the scope of the claims.

I claim:

1. In a door having a rotary knob shank; the combination of an alarm mechanism as-

sociated therewith comprising a bracket 4 having alined apertured ears and an explosive cap lug, a plunger rotatably and slidably mounted in the apertures, the plunger having a resetting arm extending from one end, a collar secured to the plunger, a coil 5 spring surrounding the plunger between the collar and one of the bracket ears, a key extending from said plunger, a reciprocative lock and release finger having a looped head through which the plunger extends, 55 the looped head being provided with a key way which is normally offset from the line of travel of the plunger key, and an actuating cam for the lock and release finger, the same being detachably secured to the 60 shank of the knob.

2. In a door having a rotary knob shank; the combination of an alarm associated therewith comprising a bracket having an audible signal mechanism associated therewith, ears extending from the bracket, a spring controlled plunger reciprocatively mounted in the ears, a reciprocative lock and release finger having a looped end through which the plunger extends, the loop being 70 provided with a key recess, a key carried by the plunger, the same being normally in frictional contact with one face of the finger head, means associated with the door knob for lifting the finger, whereby the key 75 is free to travel through the looped head thereof, the forward movement of the plunger being arranged to actuate the audible signal, and a resetting arm extending from the plunger whereby it is rotated in a resetting movement to cause the key to aline with the loop recess of said finger head.

In testimony that I claim the foregoing I have hereunto set my hand at Milwaukee, in the county of Milwaukee and State of 85 Wisconsin.

JOHN S. SPIREWKA, Jr.
